UNITED STATES PATENT OFFICE.

FRED S. PETERSON, OF SEBASTOPOL, CALIFORNIA, ASSIGNOR OF ONE-HALF TO
WILLIAM S. BORBA, OF SEBASTOPOL, CALIFORNIA.

AUTOMATIC GARAGE-DOOR.

1,275,594.

Specification of Letters Patent. Patented Aug. 13, 1918.

Application filed August 20, 1917. Serial No. 187,195.

To all whom it may concern:

Be it known that I, FRED S. PETERSON, a citizen of the United States, residing at Sebastopol, in the county of Sonoma and 5 State of California, have invented a new and useful Automatic Garage-Door, of which the following is a specification.

The object of my invention is to provide a door for buildings, and particularly garages, adapted to be automatically opened 10 on the approach of a vehicle, to permit of the entrance of the vehicle without the necessity of its coming to a standstill and which will not require manual opening of 15 the door by an attendant. It is further an object of my invention to provide a door of this character which will automatically close as soon as the vehicle has entered the building. It is further my object to provide 20 novel adjustable weighted mechanism for easily regulating the operation of the device, and to provide novel means for supporting the door in vertical position at all times and to provide novel means to cause the door to 25 move from open to closed position and vice versa, by gravity. It is further my object to provide apparatus adapted for application to either single or double doors. These 30 objects I attain by the mechanism shown in the accompanying drawings, in which—

Figure 1 is a front view of the invention applied to double garage doors; Fig. 2 is a section on line 2—2 of Fig. 1; Fig. 3 is a section on line 3—3 of Fig. 1; and Fig. 4 is 35 a detail sectional view on line 4—4 of Fig. 1.

Like letters refer to like parts in all the views.

Referring to the accompanying drawings: A and A designate suitable depressible vertical run-ways pivotally supported at opposite ends by hinges O and hingedly connected to each other by the intermediate hinge N. A lever B mounted on pivot V is operatively attached to member U. At 45 the opposite end of lever B is a projection S slidably engaging the slotted portion P of lever D. Lever D is pivotally mounted on pivot R and is provided with a slotted portion Q, at its end in which arm T on rod E 50 is slidably engaged. Rod E which is vertically slidable in guides W is operatively connected to bar Y which is supported on the building front by pivot X. Bar Y carries a suitable track F from which door 55 G is suitable suspended. Attached to the

central upper portion of door G are supporting members H suspended by pivots I from bar J which in turn is suspended by suitable arms K, to which are mounted suitable rollers L resting on track F. Bar J is 60 also provided with depending door guide members M which extend below the top of the door on both sides as shown in Fig. 2 and keep it in a straight course. Adjustably mounted on levers D and B as illustrated in Figs. 1, 2 and 3, are suitable counter weights C adjustable by means of a suitable fastening member, such as thumb screw Z.

When a vehicle approaches the door, its 70 weight on run-ways A will counteract weight C and tilt levers D and B, thus lowering rod E which moves bar Y and its track F into inclined position slanting downwardly from pivot X. In consequence of this 75 inclination of the track the weight of the door G supported by members H, J, K and L will cause the door structure to roll on rollers L to the end of track F farthest from pivot K, or in other words, the door glides to open 80 position. Depending arms M keep it parallel with the front of the building. As soon as the weight of the vehicle has left the run-way on entering the building the counter weight C on levers D and B will 85 cause the mechanism to return to its original position, thus closing the door.

It is, of course, in contemplation of my invention to arrange the device for either 90 single or double doors.

What I claim is:

1. An automatically operated door for buildings, comprising a suspended door, a tiltable track from which the door is suspended, a vertically disposed rod connected 95 to the outer end of the aforesaid track, pivotally mounted adjustably weighted members positioned beneath the door and connected with each other, one of said members being connected with the lower end of the aforesaid vertical rod, and a pivoted runway to which the other of the aforesaid weighted members is operatively connected, whereby depression of the runways will cause the door to open.

2. An automatically operated door for buildings, comprising a suspended door, a tiltable overhead track from which the door is suspended, a vertically disposed rod, pivotally mounted levers one of which is con- 100 105 110

nected with the lower end of the rod, said levers being positioned below the door, the levers being pivoted together, weights adjustably mounted on the levers to permit of 5 adjusting the operation of the device, a runway comprising sections one of which is attached to the end of one of the aforesaid

levers farthest from the vertically disposed rod, said sections having their ends hinged to each other to admit of an up and down 10 movement, whereby the door may be operated.

FRED S. PETERSON.

Copies of this patent may be obtained for five cents each, by addressing the "Commissioner of Patents, Washington, D. C."
